UNITED STATES PATENT OFFICE.

FREDERICK COATES, OF CINCINNATI, OHIO, ASSIGNOR TO FEDERAL PRODUCTS COMPANY, OF CINCINNATI, OHIO, A CORPORATION OF OHIO.

AUTO TUBE WINDER.

Application filed April 27, 1921. Serial No. 464,838.

To all whom it may concern:

Be it known that FREDERICK COATES, a citizen of the United States, residing at Cincinnati, in the county of Hamilton and 5 State of Ohio, has invented certain new and useful Improvements in Auto Tube Winders, of which the following is a specification.

This invention relates to machines for forming paper cartons or can bodies, the 10 cans being of the type having tubular bodies.

More especially the invention relates to what I preferably term a tube winder.

One important object of the invention is to provide an improved automatic machine 15 to which blanks consisting of rectangular strips of paper may be fed and which will be delivered from the machine in the form of tubular can bodies.

A second important object of the invention 20 is to provide an improved machine for forming tubular can bodies wherein improved means is used for rotating a tube former at a predetermined point in its travel over a prescribed path.

A third important object of the invention 25 is to provide an improved machine of this class having improved stripping means for removing the can body from the former.

A fourth important object of the invention 30 is to provide an improved machine of this class having an automatically operating intermittent clutch and a carrier head driven from the clutch and carrying the can former so that, at stated intervals, the rotation 35 of the former is stopped automatically while the winding and stripping operations take place.

A fifth important object of the invention 40 is the provision of a machine of this class having an improved mechanism for holding the tube or body formers against rotation as the body is wound thereon.

A sixth important object of the invention 45 is the provision, in a machine of this class, of novel mechanism for holding the glued end of a blank down on the body of the blank until the same will adhere firmly.

With the above and other objects in view, 50 the invention consists in general of certain novel details of construction and combinations of parts hereinafter fully described, illustrated in the accompanying drawings, and specifically claimed. In the accompanying drawings, like characters of refer-

ence indicate like parts in the several views, 55 and:—

Figure 1 is a plan view of the invention.

Figure 2 is a side elevation of one end of the device.

Figure 3 is a section on the line 3—3 of 60 Figure 1.

Figure 4 is a detail section on the line 4—4 of Figure 1.

Figure 5 is a detail section on the line 5—5 of Figure 1. 65

Figure 6 is a detail section on the line 6—6 of Figure 1, showing a certain stop disk used herewith.

Figure 7 is a detail section on the line 7—7 of Figure 1. 70

Figure 8 is a detail section on the line 8—8 of Figure 2.

Figure 9 is a perspective view of one of the pressing devices herewith used.

In the embodiment of the invention herein illustrated there is provided a frame 10. Journalled in this frame is a main shaft 11 which is provided with a belt pulley 12 or some other suitable form of drive. On this main shaft is a pinion 13 which meshes 75 with a gear 14 mounted on a shaft 15. At 16 is shown a clutch, the clutch being preferably of the type disclosed in my copending application, filed the 27th day of April, 1921, and bearing the Serial Number 464,831. 80

In place of the pins shown in said copending application this clutch is provided, on one of its members 17, with a series of teeth 18. On a stop shaft 20 is mounted the stop lever 21 of the clutch, this lever having rotatably mounted thereon a roller 22 in constant engagement with the cam 23 fixed on the shaft 11. Thus the rotation of the shaft 11 rotates the cam 23 and operates to free the lever 21 from the teeth 18 on each rotation of said shaft 11. In the present instance the ratio between the gears 13 and 14 is intended to be four to one and there are four of the teeth 18 so that the clutch 16 is disengaged from the shaft 15 four times 85 during each revolution of said shaft thus causing the shaft 15 to stop four times in each revolution. It will be noted that the gear ratio described is, in this instance, truly a ratio of movement rather than diameter 90 since during the disengagement of the clutch there will be a pause in the revolution of the shaft 15 it must be compensated as otherwise

the shafts 11 and 15 would not revolve in the proper ratio. On the shaft 15 is mounted a spider or former carrier 24 provided with a series of bearings 25 wherein are rotatable mounted shafts 26 each carrying a body former 27 of the type described in my copending application bearing the Serial Number 464,834 and filed the 27th day of April 1921. That is to say each of these body formers is a hollow cylinder having a central cavity 28 with lateral ports 29 leading therefrom. Carried on the shaft 11 is a gear 30 which meshes with a gear 31. Extending through a vacuum box 32 is a vacuum pipe 33 which revolves with the gear 31 and carries on its end a disk 34 provided with a recess wherein is seated a rubber clutch and packing ring 35. Mounted on the shaft 11 is a cam 36 and a lever 37 pivoted at one end, as at 38, carries a cam roller 39 engaging in the groove of the cam 36. This lever 37 operates to oscillate once in each revolution of the shaft 11 and the cam 36 is provided with a dwell 40 wherethrough the roller passes. Moreover the lever 37 is so connected to the shaft 33 as to move the latter as the lever oscillates. It will be noted that the lever 21 stops the clutch and disengages the shaft 15 at a time when a former head 27 is in alinement with the shaft 33. Also at this time the lever 37 has moved to bring the head 34 into engagement with the former 28 which is in alinement. Consequently the head 34 acts as a fringe clutch and rotates this former. At the same time the movement of the lever opens a valve 41 in a suction pipe 42, the valve being provided with operating handle 43 connected to the lever 37 by a link 44. At 45 is a bearing wherein is slidably mounted a shaft 46 carrying gripper fingers 47. Mounted slidably on each of the former heads is a stripper 48 having a rib 49 engageable, when in proper position, in grooved portions 50 of said stripper fingers. This shaft 46 is connected by pins 51 to the lever 37. These parts are so arranged and proportioned that during the disengagement of the main clutch and while one former 27 is revolved by the shaft 33 the lever 37 will oscillate once to move the stripper 48 over the former 27 just behind that former which is alined with the shaft 33. It will be seen that a suitable feed guide 52 is provided at the proper point to guide the paper strip S to the rotating former. On the head 25 are mounted pins 53 and on each of these pins is provided a sleeve 54 carrying at one end a presser finger 55 while at the other end each sleeve has an arm 56 provided at its ends with spaced prongs 57 and 58 the prong 58 being closer to the sleeve and longer than the prong 57. Projecting from each stripper 48 is a pin 59. On the shaft 15 is a sleeve 60 in which the shaft freely rotates and at one end of this

sleeve is an arcuate cam 61 having at its end a projection 62. Extending from each of the arms 56 is a finger 63 which is so arranged that when the carrier head rotates these fingers 63 are brought successively into contact with the cam 61 in such manner as to lift the presser 55 away from the former. From an inspection of Figure 3 it will be seen that the presser is kept well out of engagement with such former and upon arrival at the projection 62 is moved still further away from engagement. In order to accurately time the arrival of the pin 59 in position to be engaged between the fingers 57 and 58 there is provided on the shaft 11 a cam 64 which oscillates a lever 65 projecting from the sleeve 60. Thus at each revolution of the cam 61, just as a respective finger 63 has rested on to the projection 62 the lever 65 will be drawn forward by a spring 66 and the cam 61 slipped from beneath said finger 63 allowing the presser 55 to move toward the former. This operation takes place just as the former has been acted upon by the revolution of the shaft 33 so that when said former has made its revolution the pin 59 is engaged by the arm 58 and further revolution of the said former is stopped during the travel of the same until the cam 61 is again engaged. At this time the presser is lifted away to permit action of the stripper. It will be noted that this result is accomplished by aid of the action of the cams on the shaft 11 as well as by the action of the cam 61, these cams being in such timed relation that the pin 59 makes nearly a complete revolution during the time that the presser 55 is held outward by the lug 62, this lever being released at the proper instant to permit the pin 59 to drop between the fingers 57 and 58.

From the foregoing it will be seen that the blanks are fed successively on the former as they are brought around to position, the former being revolved once, the glued ends of the blanks held down until the stripper stop is reached. At this time the stripper operates and the former is free to receive another blank.

It will be noted that springs 67 and 68 are used to hold the presser and lever 21 in position respectively.

It is obvious that minor changes may be made in the form and construction of the invention without departing from the material principles thereof. It is not therefore desired to confine the invention to the exact form herein shown and described, but it is wished to include all such as properly come within the scope claimed.

Having thus described the invention, what is claimed as new, is:—

1. In combination, a series of rotatable can body formers, a rotating shaft carrying a suction head, means to bring said formers

successively into alinement with said shaft and temporarily hold them in such alinement, and other means to bring said suction head into engagement with the alined former whereby to rotate the former during its alinement.

2. In combination, a series of rotatable can body formers, a rotating shaft carrying a suction head, means to bring said formers successively into alinement with said shaft and temporarily hold them in such alinement, other means to bring said suction head into engagement with the alined former whereby to rotate the former during its alinement, a stripper, and means to operate said stripper on a second former during the period of rest of the first former.

3. In combination, a series of rotatable can body formers, a rotating shaft carrying a suction head, means to bring said formers successively into alinement with said shaft and temporarily hold them in such alinement, other means to bring said suction head into engagement with the alined former whereby to rotate the former during its alinement, a clamping device for holding material on said former, and operating means for the clamp device arranged to permit engagement of the clamp with the material on the former and free it from said material during successive portions of the travel of said former.

4. In combination, a series of rotatable can body formers, a rotating shaft carrying a suction head, means to bring said formers successively into alinement with said shaft and temporarily hold them in such alinement, other means to bring said suction head into engagement with the alined former whereby to rotate the former during its alinement, a stripper, means to operate said stripper on a second former during the period of rest of the first former, a clamping device for holding material on said former, and operating means for the clamp device arranged to permit engagement of the clamp with the material on the former and free it from said material during successive portions of the travel of said former.

5. In combination, a series of rotatable can body formers, a rotating shaft carrying a suction head, means to bring said formers successively into alinement with said shaft and temporarily hold them in such alinement, other means to bring said suction head into engagement with the alined former whereby to rotate the former during its alinement, and stop means for each former arranged to positively prevent rotation of the former during the passage of the former over a predetermined portion of its path of travel.

6. In combination, a series of rotatable can body formers, a rotating shaft carrying a suction head, means to bring said formers

successively into alinement with said shaft and temporarily hold them in such alinement, other means to bring said suction head into engagement with the alined former whereby to rotate the former during its 70 alinement, stop means for each former arranged to positively prevent rotation of the former during the passage of the former over a predetermined portion of its path of travel, a stripper, and means to operate 75 said stripper on a second former during the period of rest of the first former.

7. In combination, a series of rotatable can body formers, a rotating shaft carrying a suction head, means to bring said formers 80 successively into alinement with said shaft and temporarily hold them in such alinement, other means to bring said suction head into engagement with the alined former whereby to rotate the former during its 85 alinement, stop means for each former arranged to positively prevent rotation of the former during the passage of the former over a predetermined portion of its path of travel, and a clamping device for holding 90 material on said former, and operating means for the clamp device arranged to permit engagement of the clamp with the material on the former and free it from said material during successive portions of 95 the travel of said former.

8. In combination, a series of rotatable can body formers, a rotating shaft carrying a suction head, means to bring said formers 100 successively into alinement with said shaft and temporarily hold them in such alinement, other means to bring said suction head into engagement with the alined former whereby to rotate the former during its alinement, stop means for each former arranged to positively prevent rotation of the former during the passage of the former over a predetermined portion of its path of travel, a clamping device for holding 105 material on said former, and operating 110 means for the clamp device arranged to permit engagement of the clamp with the material on the former and free it from said material during successive portions of the travel of said former.

9. In combination, a revolving carrier head, a series of formers arranged in circular alinement to said head, means to stop the revolution of said head intermittently and arranged to cause the formers to stop successively at a predetermined station, driving means to rotate each former during its stoppage at said station, a clamping device for holding said material on said formers, said clamping device being mounted on and revolving with the head, latch means for holding the formers against rotation during a predetermined portion of said travel, and operating means for the clamping device arranged to permit engagement of the clamp 120 125 130

with the material on the formers and free it from said material during successive portions of the travel of said formers, said operating means being also arranged to free the 5 latch device during the stoppage of each former at its station.

10. In combination, a revolving carrier head, a series of formers arranged in circular alinement on said head, means to intermittently stop the revolution of said head arranged to cause the formers to stop successively at a predetermined station, driving means to rotate each former during its stoppage at said station, stop means for each former arranged to positively prevent rotation of the former over a predetermined portion of its path of travel, a clamping device revoluble with the head and for holding material on said former, and operating means 15 for the clamp device arranged to permit engagement of the clamp with the material on the former and free it from said material during successive portions of the travel of said former, said operating means being also 20 arranged to free the stop means simultaneously with the freeing of the clamp.

11. In combination, a revolving carrier head, a series of formers arranged in circular alinement on said head, a clutch normally 30 operative to drive said head, means to intermittently free the clutch and stop the revolution of said head and arranged to cause the formers to stop successively at a predetermined station, driving means to rotate each former during its stoppage at said station, a clamping device revoluble with the head and for holding material on said former, and operating means for the clamp device arranged to permit engagement of the clamp 35 with the material on the former and free it from said material during successive portions of the travel of said former, said operating means being also arranged to free the stop means simultaneously with the freeing of the clamp.

45. 12. In combination, a revolving carrier

head, a series of formers arranged in circular alinement on said head, a clutch normally operative to drive said head, means to intermittently free the clutch and stop the revolution of said head and arranged to cause the formers to stop successively at a predetermined station, driving means to rotate each former during its stoppage at said station, stop means for each former arranged to positively prevent rotation of the former over a predetermined portion of its path of travel, a clamping device revoluble with the head and for holding material on said former, and operating means for the clamp device arranged to permit engagement of the clamp with the material on the former and free it from said material during successive portions of the travel of said former, said operating means being also arranged to free the 65 stop means simultaneously with the freeing of the clamp.

13. In combination, a revolving carrier head, a series of formers arranged in circular alinement on said head, a clutch normally 70 operative to drive said head, means to intermittently free the clutch and stop the revolution of said head and arranged to cause the formers to stop successively at a predetermined station, driving means to rotate each 75 former during its stoppage at said station, stop means for each former arranged to positively prevent rotation of the former over a predetermined portion of its path of travel, a clamping device revoluble with the head 80 and for holding material on said former, and operating means for the clamp device arranged to permit engagement of the clamp with the material on the former and free it from said material during successive portions of the travel of said former, said operating means being also arranged to free the 85 stop means simultaneously with the freeing of the clamp.

In testimony whereof I affix my signature.

FREDERICK COATES.
